UNITED STATES PATENT OFFICE

EUGEN BURG, OF ESSEN, GERMANY

FIREPLACE

Application filed October 25, 1927, Serial No. 228,545, and in Germany November 4, 1926.

My invention relates to improvements in fire places, and more particularly in fire places for the combustion of powdered fuel, in which the combustion takes place within a combustion chamber provided in connection with the chamber to be heated, and in which secondary air is admitted through passages made in the wall of the combustion chamber. The object of the improvements is to provide a fire place of this type in which the said passages are constructed so that they can be varied in cross-sectional area for adapting the same to varying conditions, and more particularly to the heat to be developed and the temperature of the air. In the preferred construction of the fire place the regulating means for a part of the said passages or for all the said passages are connected to a common operating member. In one embodiment of the invention the passages are provided between blocks or bricks of refractory material adapted to be moved relatively to each other for varying the passages provided between adjacent blocks or bricks, and such displacement of the blocks or bricks may be brought about for example by rocking the bricks or blocks or by shifting the same in radial or substantially radial direction.

For the purpose of explaining the invention two examples embodying the same have been shown in the accompanying drawings in which the same letters of reference have been used in all the views to indicate corresponding parts. In said drawings,

Fig. 1, is a sectional elevation taken on the line 1—1 of Fig. 2 and showing the combustion chamber,

Fig. 2, is a sectional elevation taken on the line 2—2 of Fig. 1,

Fig. 3, is a sectional elevation taken on the line 3—3 of Fig. 4 and showing a modification of the fire place, and

Fig. 4, is a sectional elevation taken on the line 4—4 of Fig. 3.

In the example shown in Figs. 1 and 2 the fire place comprises a chamber *j* which is to be heated by the powdered fuel, a cylindrical combustion chamber *v* located in front of the chamber *j*, and a burner *s* of any known or preferred construction, the said burner being

disposed axially of the chamber *v* and delivering fuel and air into the same, as is known in the art. The chamber *v* comprises an end wall *v*¹ and a cylindrical wall composed of adjacent rings of segmental bricks or blocks *a* made from refractory material, the bricks or blocks of each ring being spaced from each other at the end faces thus providing radial or substantially radial passages *t*. The rings of blocks or bricks are surrounded by a jacket *p* connected with a supply *r* of air under pressure, so that secondary air supplied through the pipes *r* is delivered through the passages *t* into the combustion chamber *v*.

The bricks or blocks *a* are supported in longitudinal rows on rods *b* passing through holes made in the said blocks, and the said rods are supported on two or more pairs of annular plates *c* and *d*. As appears more particularly from Fig. 1, the plates *c* are formed with radial slots *h* engaged by the parts or rods *b*, while the plates *d* are provided with slots *h* disposed at acute angles to the circle on which the rods *b* are located. The annular plates *c* provided with the radial slots *h* are fixed to a stationary part for example to the jacket *p* as is indicated at *p*¹, while the annular plates *d* are movable in circumferential direction. Thus, by moving the plates *d* the rods *b* are moved in radial direction inwardly or outwardly while being guided in the slots *h*, and they carry along the bricks or blocks *a* thus increasing or reducing the cross-sectional area of the passages *t*. Suitable means are provided for thus moving the plates *d*. To show what may be done the plates *c* and *d* are provided with arms *n* and *o* formed at their top ends with internally screw-threaded eyes, and the said eyes are engaged by a bolt *m* provided at its ends with right hand and left hand screw threads. To the bolt *m* a hand wheel *e* is secured by means of which the bolt is screwed within the arms *n* and *o* for shifting the rings *b* and *c* relatively to each other in circumferential direction.

The blocks are thus arranged in longitudinal rows; each row being carried by one of the rods and these rows are arranged side by side in the enclosing wall of the chamber *v*,

which, as illustrated in the drawings, is annular. The jacket or casing p must be slotted as shown at d^1 for the arm o to permit movement of the ring b .

5 In the modification shown in Figs. 3 and 4, the end walls of the bricks or blocks a^1 are disposed at acute angles to the circumference of the rings provided by the blocks, so that the secondary air is delivered through the 10 passages t^1 provided between adjacent blocks more or less in tangential direction. The blocks a^1 are formed with square holes engaged by longitudinal rods u of square cross-section. By turning the said rods about their 15 longitudinal axes the area of the passages t^1 is varied. The rods u are pivotally mounted in annular plates c^1, c^2 provided at opposite ends of the combustion chamber and fixed to the end walls thereof. At one of their ends 20 the parts or rods u have radial arms f fixed thereto, which arms are formed at their outer ends with slots f^1 engaged by pins w secured to an annular plate g . By shifting the said 25 said annular plate in circumferential direction the arms f and rods u are rocked about the longitudinal axes of the said rods, so as to set the blocks a^1 in different positions. For thus shifting the plate g similar means 30 may be provided as have been described with reference to Figs. 1 and 2, which means comprise an internally screw-threaded eye o^1 made integral with the ring g , an internally screw-threaded and relatively fixed eye n^1 integral with the ring c^1 , a bolt m^1 formed at 35 its ends with screw threads of opposite pitch and engaging said screw-threaded eyes, and a hand wheel e^1 fixed to said bolt.

In Figs. 3 and 4 the blocks are also arranged in longitudinal rows and these rows 40 are placed side by side in the enclosing wall of the chamber v , which is shown as annular the same as in Figs. 1 and 2. Obviously the chamber or fireplace need not be circular in cross-section but it may be square or have 45 some other form and the same arrangement of blocks may be followed in a wall that is arched or straight instead of annular.

Further in Figs. 3 and 4 the rear ring c^2 adjacent the chamber j may be associated 50 with arms f , a ring or plate g , and the other means for shifting, the same as the ring c^1 .

The general construction of the fire place shown in Figs. 3 and 4 is the same as that described with reference to Figs. 1 and 2, and 55 the same letters of reference have been used to indicate similar parts.

In both examples the air supplying chamber provided between the packet p and the circumferential wall of the combustion 60 chamber is divided by a partition x , x^1 into sectional chambers, and the pipe r is divided into two branches each connected with one of said sectional chambers. If desired the 65 sets of blocks a, a^1 covered by the said sections may be provided with independent means

for varying the area of the passages t, t^1 , for which purpose the rods b, u are divided at the middle and each sectional rod is provided with setting means of its own, and additional supporting bearing rings at the middle of the 70 chamber v .

While in describing the invention reference has been made to particular examples embodying the same, I wish it to be understood that my invention is not limited to the 75 constructions shown in the drawings, and that various changes may be made in the general arrangement of the apparatus and the construction of its parts without departing from the invention.

I claim:

1. A fire place, comprising a combustion chamber having its wall composed of blocks in longitudinal rows spaced from one another for providing passages for the admission of secondary air, means for supplying secondary air through said passages, means for displacing the rows of said blocks relatively to one another so as to vary the cross-sectional area of the passages provided between the same, and means for supplying fuel into said combustion chamber.

2. A fire place, comprising a combustion chamber having its wall composed of annularly disposed longitudinal rows of blocks spaced from one another to provide passages for the admission of air, means connected with the longitudinal rows of blocks for setting the blocks of the rows in different positions for varying the area of the said passages, and means for supplying fuel to the combustion chamber.

3. A fire place, comprising a combustion chamber having its wall composed of sets of annularly disposed longitudinal rows of blocks spaced from one another to provide passages for the admission of air, means connected with adjacent rows of blocks for displacing the blocks in radial direction so as to vary the cross-sectional area of the said 105 passages, and means for supplying fuel to the combustion chamber.

4. A fire place, comprising a combustion chamber having its wall composed of sets of annularly disposed longitudinal rows of blocks spaced from each other to provide passages for the admission of air to the combustion chamber, rods supporting the adjacent longitudinal rows of blocks, means connected with said rods for moving the same and the blocks connected therewith so as to vary the cross-sectional area of said passages, and means to supply fuel to said combustion chamber.

5. A fire place, comprising a combustion chamber having its wall composed of annularly disposed longitudinal rows of blocks spaced from each other to provide passages for the admission of air to the combustion chamber, rods supporting the adjacent rows 125

of blocks, pairs of rings around said rows of blocks formed respectively with cooperating slots disposed angularly of each other and engaging said rods, means for shifting said rings relatively to each other in circumferential direction, and means for supplying fuel to said combustion chamber.

6. A fire place, comprising a combustion chamber having its wall composed of annularly disposed longitudinal rows of blocks spaced from each other to provide passages for the admission of air to the combustion chamber, rods supporting the adjacent rows of blocks, pairs of rings around said rows of blocks formed respectively with radial slots and slots disposed angularly of said radial slots, means to displace the rings provided with the angularly disposed slots relatively to the rings provided with radial slots, and means for supplying fuel to said combustion chamber.

7. A fire place, comprising a combustion chamber having its wall composed of annularly disposed longitudinal rows of blocks spaced from each other to provide passages for the admission of air to the combustion chamber, rods supporting the adjacent rows of blocks, pairs of rings around said rows of blocks formed respectively with cooperating slots disposed angularly of each other and engaging said rods, bolts formed at their ends with screw threads of opposite pitch engaging in corresponding screw-threaded portions of the rings of the said pairs, hand wheels on said bolts for turning the same, and means for supplying fuel to said combustion chamber.

8. A fire place, comprising a combustion chamber having its wall composed of longitudinal rows of blocks having their end faces disposed angularly of the corresponding radii and spaced from one another to provide substantially tangential passages, means for supplying air through said passages, longitudinal rods fixed to the longitudinal rows of blocks, means to rock said rods and the blocks carried thereby for varying the distances between the end faces thereof, and means to supply air through the said passages.

50 9. A fire place, comprising a combustion chamber having its wall composed of longitudinal rows of blocks having their end faces disposed angularly of the corresponding radii and spaced from one another to provide substantially tangential passages, means for supplying air through said passages, longitudinal rods fixed to the longitudinal rows of blocks, arms fixed one to each of said rods, a ring to which the free ends of said arms are jointed, means to shift said ring in circumferential direction, and means to supply air through said passages.

10. A fire place, comprising a combustion chamber having its wall composed of longitudinal rows of blocks having their end faces

disposed angularly of the corresponding radii and spaced from one another to provide substantially tangential passages, means for supplying air through said passages, longitudinal rods fixed to the longitudinal rows of blocks, arms fixed one to each of said rods, a ring to which the free ends of said arms are jointed, a screw screwing in a nut formed on said ring and engaging a relatively fixed part, a hand wheel carried by said screw for turning the same, and means to supply fuel to said combustion chamber.

11. A fire place, comprising a combustion chamber having a cylindrical wall composed of longitudinal rows of blocks spaced from one another to provide passages, a jacket around said cylindrical wall and divided transversely into sections, means to supply air through said jacket and passages, separate means for displacing the blocks covered by the sections of said jacket so as to vary the area of said passages, and means to supply fuel to said chamber.

12. A fire place, comprising a combustion chamber having a wall composed of longitudinal rows of blocks, longitudinal elements supporting the rows of blocks spaced from one another to provide passages for the admission of air into the chamber, said longitudinal elements extending through the blocks, and being supported for adjustment relatively to each other for adjusting the relative positions of the rows of blocks whereby to vary the cross sectional area of the passages.

13. A fire place, comprising a combustion chamber having a wall composed of adjacent longitudinal rows of coating blocks, longitudinal elements carrying the rows of blocks, the longitudinal elements extending through the blocks and at least one of the longitudinal elements being independently movable to adjust the row of blocks carried thereby so as to produce with the adjacent rows of blocks passage defining walls forming passages into the chamber for the admission of air thereinto.

14. A fire place, comprising a combustion chamber having a wall composed of adjacent longitudinal rows of coating blocks, longitudinal elements supporting the rows of blocks, the longitudinal elements extending through the blocks for the support of the same and being supported for adjustment relatively to each other for adjusting the relative positions of the rows of blocks so as to provide passages into the chamber for the admission of air thereinto, and a jacket forming an air space with the rows of blocks to receive air to be admitted through the passages into the chamber.

In testimony whereof I hereunto affix my signature.

EUGEN BURG.
